United States Patent Office.

JOHN LETCHWORTH, OF PHILADELPHIA, PENNSYLVANIA, ASSIGNOR TO
HARTELL AND LETCHWORTH, OF SAME PLACE.

Design No. 3,852, dated February 15, 1870.

DESIGN FOR SHADE FOR GAS OR LAMP-BURNERS.

The Schedule referred to in these Letters Patent and making part of the same.

I, JOHN LETCHWORTH, of Philadelphia, county of Philadelphia, State of Pennsylvania, have invented a Design for a Shade for Gas or Lamp-Burners, of which the following is a specification.

The figure in the accompanying drawing represents, in outline, a lamp-shade made according to my design, the form of the shade being that of an inverted frustum of a cone, defined by the inclined lines *a a*, the upper horizontal line *b*, and the flange *d*, irrespective of any ornamentation of the shade by grinding, cutting, coloring, or otherwise.

I claim the design for a lamp-shade, substantially as described, and as illustrated in and by the accompanying drawing.

In testimony whereof I have signed my name to this specification in the presence of two subscribing witnesses.

JNO. LETCHWORTH.
